Primary Examiner — Ania Aman

(57) **CLAIM**

The ornamental design for a heat dissipation mesh as shown and described.

DESCRIPTION

FIG. 1 is a front-right-top perspective view of the heat dissipation mesh showing my new design;

FIG. 2 is a front elevational view thereof;

FIG. 3 is a front perspective view showing the application thereof;

FIG. 4 is a rear perspective view showing the application thereof;

FIG. 5 is a front elevation view showing the application thereof;

FIG. 6 is a rear elevation view showing the application thereof;

FIG. 7 is a left side elevation view showing the application thereof;

FIG. 8 is a right side elevation view showing the application thereof;

FIG. 9 is a top plan view showing the application thereof; and,

FIG. 10 is a bottom plan view showing the application thereof.

The broken lines showing of the heat dissipation mesh is provided for the purpose of illustrating environmental structures and form no part of the claimed design.

1 Claim, 8 Drawing Sheets
